STABILIZATION OF N,N' DI-SECONDARY-BUTYL p-PHENYLENE DIAMINE

Joseph A. Chencicek, Riverside, Ill., assignor to
Universal Oil Products Company, Chicago, Ill.,
a corporation of DelawareNo Drawing. Application March 27, 1947,
Serial No. 737,717

6 Claims. (Cl. 260—577)

1

This invention relates to the stabilization of N,N' di-secondary-butyl p-phenylene diamine and more particularly to a method of preventing discoloration and other undesirable deterioration which amino compounds or solutions of amino compounds undergo upon exposure to air and/or light.

The present invention is particularly applicable to the treatment of aryl amino compounds and may also be utilized for preventing discoloration of aliphatic amino compounds. However, aliphatic amino compounds in general do not readily undergo discoloration and usually are satisfactory for use without the necessity of adding an inhibitor.

Aryl amino compounds are utilized for many purposes, such as intermediates in the preparation of various chemical compounds or as additives to hydrocarbons or other organic materials. In many cases the discoloration of amino compounds is undesirable and renders the amino compounds unsatisfactory for the desired use.

The present invention is particularly applicable for preventing discoloration of various amino compounds added to unstable organic materials as inhibitors to prevent oxidative deterioration of the organic compounds. For example, particularly effective inhibitors comprise N-N'-di-alkyl p-phenylene diamines and N-alkyl p-aminophenols but these inhibitors tend to undergo discoloration in the presence of oxygen-containing gases such as air.

Another class of aryl amino compounds to which the present invention is particularly applicable comprises xylidine and similar type compounds which are used as additives to hydrocarbons and particularly gasoline in order to improve the antiknock characteristics thereof.

In a broad embodiment the present invention relates to a method of preventing the discoloration of amino compounds which comprises adding thereto a small but effective amount of an aldehyde.

In a specific embodiment the present invention relates to a method of preventing discoloration of N-N'-dialkyl p-phenylene diamines which comprises adding thereto from about 0.01% to about 5% by weight of an aliphatic aldehyde.

In another specific embodiment the present invention relates to a method of preventing discoloration of N-alkyl p-aminophenols which comprises adding thereto from about 0.01% to about 5% by weight of an aliphatic aldehyde.

In another embodiment the present invention relates to a novel composition of matter com-

2

prising an aryl amino compound and an aliphatic aldehyde.

Various well known inhibitors which have been proposed heretofore for other uses, such as preventing discoloration or gumming in gasolines, have proved unsatisfactory for preventing the discoloration of aryl amino compounds and in some cases these compounds have actually accelerated the discoloration of the amino compound. I have discovered that the compounds of the present invention are effective in preventing discoloration of amino compounds.

The compounds of the present invention are particularly advantageous in that they are readily available, are relatively inexpensive, are miscible with aromatic amino compounds and do not adversely affect the inhibiting potency of the amino compounds when the latter are used as oxidation inhibitors in organic compounds. In addition, the aldehydes of the present invention are readily miscible in organic compounds, and particularly hydrocarbons, to which the amino compounds are added as oxidation inhibitors.

The stabilizing compounds of the present invention comprise aldehydes and preferably aliphatic aldehydes, including both the saturated and unsaturated aldehydes. Preferred stabilizing compounds include propionaldehyde, butyraldehyde, valeraldehyde, heptaldehyde, etc. as representative of saturated aliphatic aldehydes, and citral, citronellal, etc. as representative of unsaturated aliphatic aldehydes. Aromatic aldehydes include benzaldehyde, salicylaldehyde, vanillin, camphor, etc. It is understood that the various stabilizing compounds which may be utilized in accordance with the present invention are not necessarily exactly equivalent in their effectiveness in retarding the discoloration of amino compounds.

The stabilizing compounds of the present invention will generally be employed in amounts of from 0.01% to about 5% by weight of the amino compound. In most cases the aldehyde will be added to the amino compound to stabilize the same while in storage and prior to use, although it is understood that, when desired, the aldehyde may be added to organic materials containing the amino compound.

The following examples are introduced to illustrate further the novelty and utility of the present invention but not with the intention of unduly limiting the same.

Various aldehydes were added in an amount of 1% by weight to different samples of a gasoline inhibitor comprising N-N'-di-secondary-butyl p-phenylene diamine.

The samples were stored in 4 oz. bottles and exposed to the air through a one inch length of 0.5 mm. I. D. capillary tubing inserted in the stopper. The N. P. A. color was determined in a Union colorimeter after definite periods of storage at room temperature.

EXAMPLE 1

The N-N'-di-secondary-butyl p-phenylene diamine used in this example reached an N. P. A. color of 8 in 19 hours. The results of the addition of two aldehydes to different samples of the p-phenylene diamine are indicated below.

Table 1

Additive	N. P. A. Color After Storage for the Following Number of Hours						
	0	2	19	43	67	91	163
None	5	7	8	>8			
n-butyraldehyde	7	7	7	7½	7½	8	8
Citronellal	5	6½	7½	7½	8	8	

It will be noted that n-butyraldehyde increased the time of storage to reach an N. P. A. color not greater than 8 from 19 hours to 163 hours. Citronellal increased its storage period from 19 hours to 91 hours.

EXAMPLE 2

Another sample of N-N'-di-secondary-butyl p-phenylene diamine was stabilized with various aldehydes. This sample of N-N'-di-secondary-butyl p-phenylene diamine was prepared under different conditions than the sample of p-phenylene diamine used in Example 1 and was more resistant to color change in the presence of air. This particular sample required 210 hours before reaching a N. P. A. color of 8. The results of these tests are indicated in the following table.

4
consisting of n-butyraldehyde, citronella, heptaldehyde, citral and benzaldehyde.

2. N-N'-di-secondary butyl p-phenylene diamine containing from about 0.01% to about 5% by weight of heptaldehyde.

3. N-N'-di-secondary-butyl p-phenylene diamine containing from about 0.01% to about 5% by weight of n-butyraldehyde.

4. A method of preventing discoloration of 10 N-N'-di-secondary-butyl p-phenylene diamine which comprises adding thereto from about 0.01% to about 5% by weight of an aldehyde selected from the group consisting of n-butyraldehyde, citronella, heptaldehyde, citral and 15 benzaldehyde.

5. A method of preventing discoloration of N-N'-di-secondary-butyl p-phenylene diamine which comprises adding thereto from about 0.01% to about 5% by weight of heptaldehyde.

20 6. A method of preventing discoloration of N-N'-di-secondary-butyl p-phenylene diamine which comprises adding thereto from about 0.01% to about 5% by weight of n-butyraldehyde.

JOSEPH A. CHENICEK.
